UNITED STATES PATENT OFFICE.

FRIEDUS M. WALKER, OF DETROIT, MICHIGAN, ASSIGNOR TO IDEAL BOILER WATER SUPPLY COMPANY, A CORPORATION OF THE DISTRICT OF COLUMBIA.

BOILER-FEEDER.

SPECIFICATION forming part of Letters Patent No. 780,922, dated January 24, 1905.

Application filed April 18, 1904. Serial No. 203,620.

To all whom it may concern:

Be it known that I, FRIEDUS M. WALKER, a citizen of the United States, residing at Detroit, county of Wayne, State of Michigan, have invented a certain new and useful Improvement in Boiler-Feeders; and I declare the following to be a full, clear, and exact description of the invention, such as will enable others skilled in the art to which it pertains to make and use the same, reference being had to the accompanying drawings, which form a part of this specification.

This invention relates to boiler-feeders, and has for its object an improved automatic boiler-feeder in which the valves between the feeder and the water-supply and between the feeder and the boiler are automatically actuated by the varying weight of a tank and a weight counter thereto; the counterweight remains constant, and the weight of the tank is variable by varying the quantity of water therein. In boiler-feeders of this character the tank in which the water is temporarily stored during the time it is employed to actuate the valve must be located above the normal high-water line in the boiler. In consequence of such location there is a tendency for all water in the tank to empty into the boiler, following which the tank, being lighter than the counterweight, rises and opens the valves to allow refill-water to enter, and the refill-water causes the tank to fall and open the valves to allow it to discharge into the boiler, which continues until the boiler becomes more than properly full.

The object of this invention is to so arrange the connections between the tank and the boiler that after the water rises to the proper level in the boiler the steam-pressure in the boiler acts to prevent the refill of the empty and light tank.

In the drawings, Figure 1 is a diagrammatic illustration of the boiler-tank and the connecting-pipe. Fig. 2 is a plan view of pipe connections at the top of tank. Fig. 3 is a plan view of pipe connections at the bottom of tank.

A indicates the boiler; B, the tank. The

tank is supported on any suitable standard 2 by jointed pipe connections, which afford 5° facilities for the flow of the water and the steam into and out of the tank and also furnish a support on which the tank swings. The tank B is provided with a counterweight W, the stem of which is pivotally connected 55 at 3 to the standard 2 and connected by a link 4 to the pipe 5, which enters the tank B on its under side. The pipe 5 is pivotally connected to a link-pipe 6, and the link-pipe 6 is connected by a joint connection to 60 the feed-pipe 7, that enters the boiler and delivers water into the boiler near the bottom thereof.

A feed-pipe 8 from any suitable source of supply leads into pipe 7, and both pipes 7 65 and 8 are provided with valves of the globe-valve type, which valves are actuated by levers. The lever 7^a, which actuates the valve in the pipe 7, is fulcrumed on a stud 7^b, that rises from the valve-casing between the 7^c valve and the horizontal portion of the pipe 5. The end of the lever is bent around the horizontal portion of the pipe 5. Provision is made for the necessary play of the horizontal part of the pipe 5 in the loop of the lever, so 75 that they may both swing on their independent pivotal points without binding.

The valve in the pipe 8 is between the post 8^b, to which the lever 8^a is fulcrumed, and the horizontal part of the pipe, around which the 8^c end of the lever 8^a is bent into a loop 8^c. At the top end of the tank there is a single pipe 9 with a horizontal part and with a link connection 91, by which the horizontal part 9 is connected with the pivot-coupling 92, from 85 which branches an exhaust-pipe 93 and a pipe 94, that leads down to a point in a line with the normal level with the water in the boiler. Here this pipe turns and for a space is continued in the pipe 94^a at the normal level at 90 which it is desired to keep the water in the boiler. Pipe 94^a forks, and one branch, 95, passes into the boiler in the steam-space above the normal line of the water, and the part 96 passes into the boiler below the normal water- 95 level line.

An upright part of the branch 96 is furnished with a check-valve that seats upward.

The two pipes 93 and 94 are both fitted with valves of the globe type, actuated by levers 5 9^a and 9^b, similar in construction and mode of operation to the levers 7^a and 8^a, already described.

In operation the machine is set to open the valves 81 and 9^c and close the valves 71 and 10 9^d. This allows free ingress of the water to the tank B and a free exit of confined air or steam through the exhaust-pipe 93. At the same time the steam-inlet through pipe 94 is closed, and the outlet into the boiler through 15 pipe 7 is closed, and the tank B fills through the pressure of water in the source of supply. When the tank B has filled to overbalance the weight W, the tank drops. This closes the valves 81 and 9^c in exhaust-pipe 93 and opens 20 the valve 9^d in pipe 94 and valve 71 in inlet-pipe 7. The water in the tank B is now balanced between the steam-pressure in the top of the boiler and the equal water-pressure in the bottom of the boiler and flows by gravity 25 into the boiler, provided the horizontal portion 94^a of the steam-pipe is above the water-level. As soon, however, as the water in the boiler rises to a level with the horizontal portion 94^a that part fills and remains filled with 30 water, through which steam cannot pass, but through which water will pass, driven by the force of the steam, and should the tank fill with water to an extent to cause it to drop and open the water-inlet into the boiler and 35 the valve in the pipe 94, leading into the top of the tank, the tendency is to force the water in the pipe 94^a into the top of the tank B and to produce a circulation or flow of water

from the boiler through the tank. The flow, however, is checked by the check-valve 97, 40 which only allows it to take place intermittently, because as soon as a flow is set up the force of the flowing water actuates the check-valve and stops the flow, which is only taken up again after the flow is quieted to an extent 45 to allow the check-valve to drop.

What I claim is—

1. In an automatic boiler-feeder, in combination with the vertically-reciprocating tank provided with suitable supply and discharge 50 pipes, means for actuating the valves in the said pipes by the reciprocation of said tank, a pipe leading into the top of said tank from the boiler provided with a horizontal portion in the normal high-water line of said boiler, 55 and pipes branching therefrom, one branch leading into the boiler above the high-water line and one below, substantially as described.

2. In an automatic boiler-feeder, in combination a reciprocating tank provided with 60 suitable supply and discharge pipes, means for actuating the valves in said pipes by the reciprocation of said tank, a pipe leading into the top of said tank from the boiler, provided with a horizontal portion in the normal high-water line of said boiler, pipes branching 65 therefrom leading into the boiler above the high - water line and one below, the latter branch being provided with a check-valve, substantially as described.

In testimony whereof I sign this specification in the presence of two witnesses.

FRIEDUS M. WALKER.
